UNITED STATES PATENT OFFICE.

RUBÉN GONZALEZ, OF MEXICO, MEXICO.

EXTENSIBLE PULLEY.

Application filed December 23, 1922. Serial No. 603,633.

To all whom it may concern:

Be it known that I, RUBÉN GONZALEZ, a citizen of the United Mexican States, residing at Mexico city, Federal District, Mexico, have invented certain new and useful Improvements in Extensible Pulleys, of which the following is a specification.

This invention relates to an extensible pulley especially used in cigarette making machines for the conveying belt which carries the strip of paper loaded with tobacco. Such pulleys are covered with a non-skid ribbon which after use becomes flattened whereby the periphery of the pulley is somewhat reduced, so that one of the two simultaneously cut cigarettes becomes a little shorter and the brand or trade-mark printed on the paper strip with little by little come more and more toward the end of the cigarette.

Sectional extensible pulleys have also been used, but the non-skid ribbon is rapidly worn out at the several openings between the sections. Other pulleys are formed by a crown through the periphery of which extensor sections pierce, so as to tighten the ribbon by enlarging the diameter.

The object of my invention is to facilitate a device which will both allow the tightening of the ribbon and augment the periphery of the pulley, but in two independent operations.

In the drawings:

Fig. 1 is a plan view of the pulley;

Fig. 2 a section on line A—B;

Fig. 3 a plan view of one half of the pulley; and

Fig. 4 a section on line C—D.

The pulley comprises a support disk (1) with hub (2), the inner extension (3) of which is threaded at (4) to engage with an expulsing nut pinion (5) having a conical exterior.

On the inner surface of the disk (1) are attached the guide housings (6) for the extensors (7) provided with heads (8) on one end, while the opposite ends (9) are cut to an incline, so as to correspond with the conical portion of the pinion (5). An extensible ring (10) is held between the support disk (1) and the cover disk (11), screws (12) passing through the cover (11) to engage in the holes (13) of the housings (6). Between the housings is mounted a tubular pinion

(14) having teeth (15) and a shoulder (16) for braking. The interior of said pinion has a square bore (17) into which a key may be inserted for expanding the periphery of the ring (10). Both ends of the pinion (14) are supported in the disk (1) and the cover (11).

On a small support (18) fastened to the inside of the disk (1) is the locking lever (20) pivoted at (19); one end being provided with the bifurcation which when pressed upon the shoulder (16) when the opposite end of the lever is raised by the pressure screw (21), piercing through the disk (1), locks the pinion.

The extensible ring (10) carries two stirrups (22) into which are inserted the stop pins (23) fastened to the disk (1) so as to stop the ring from turning.

In order to tighten the non-skid ribbon (24) independently of the expansion of said ring (10), the ring is provided with the stationary fastener comprising the support (25), the lever (26) and the pressure screw (27). One end of the non-skid ribbon (24) is grasped by the stationary fastener while the other end is caught by an adjustable fastener and tightener, comprising the bridge (28) pivoted at (29) to a support (30) on the ring (10), and on the same bridge (28) is a support (31) with the pivot (32), so that the bridge (33) may balance and clamp the ribbon against the bridge piece (28) when the screw (34) is operated.

Now, in order to tighten the ribbon over the ring (10), the screw (35) passing through an ample groove in the bridge piece (33) cooperates with the nut-block (36) provided with trunnions (37), and the bridge (28) will oscillate on the pivot (29) when being separated from the interior of the ring (10).

In other systems having a ring formed by sectors, the ribbon is tightened by expanding the ring, but in my system there is a decided double action consisting in expanding the ring by means of the extensors and leaving but one opening between the two ends adjoining the ring; and then stretching the non-skid ribbon over the ring where by both actions are entirely independent.

In all other systems the ribbon is stretched due to the expansion of the ring. My device operates as follows:

One end of the ribbon (24) is caught by

a stationary clamp, and the other end by the adjustable clamp, then using the screw (35) the ribbon is tightened. The pulley is now mounted and fastened on the shaft and by 5 inserting the key (not shown) into the square bore (17) the pinion (14) may be turned, so that due to the teeth (38) of the nut-pinion (5) having engagement with said pinion, the conical part will exert pressure 10 on the extensors (7) in a uniform manner, and the heads (8) will expand the ring to the exact required periphery of the pulley.

Before the diameter of the pulley can be 15 modified, the screw (21) is loosened, otherwise the pinion (14) could not be turned.

Once the adjustment is obtained, the locking screw (21) is again operated so as to press the other end of the lever against the 20 shoulder.

Having thus described my invention what I claim is:

1. An expandible pulley comprising an integral hub and supporting disk; guide housings mounted on said disk; a cover secured to said housings; an expandible ring between said cover and disk and having two ends; an extensor in each housing adapted to cooperate with said ring; means on said 25 hub coacting with said extensors for increasing the diameter of said ring; and means 30

on the ends of said ring for stretching a ribbon on the outside surface of the ring.

2. An expandible pulley comprising a hub and supporting disk; a cover for said hub; a 35 ring mounted between said disk and cover and having two ends; extensors mounted for radial movement on said disk adapted to cooperate with said ring; means on said hub adapted to coact with said extensors to 40 change the diameter of said ring; and means on the ends of said ring comprising clamps for securing a ribbon on the outside of said ring.

3. An expandible pulley comprising a hub 45 and supporting disk; guide housings mounted on said disk; a cover secured to said housings; a ring between said cover and disk and having two ends; an extensor in each housing adapted to cooperate with said 50 ring; means on said hub adapted to operate the extensors radially to change the diameter of the ring; locking means for locking said first-named means in any desired position; and means for securing the ends of 55 a ribbon at the ends of said ring to provide a ribbon on the outside of the ring; substantially as described.

In testimony whereof I have affixed my signature.

RUBÉN GONZALEZ.
